Primary Examiner — John Windmuller(74) *Attorney, Agent, or Firm* — Clause Eight IPS; Michael Catania(57) **CLAIM**

The ornamental design for an antenna, as shown and described.

DESCRIPTION

FIG. 1 is a top plan view of an antenna with a base in broken lines.

FIG. 2 is a bottom plan view of the antenna of FIG. 1 with a base in broken lines.

FIG. 3 is a side elevation view of the antenna of FIG. 1 with a base in broken lines.

FIG. 4 is a front view of the antenna of FIG. 1 with a base in broken lines.

FIG. 5 is a bottom perspective view of the antenna of FIG. 1 with a base in broken lines; and,

FIG. 6 is a top perspective view of the antenna of FIG. 1 with a base in broken lines.

The broken lines are for illustration purposes only and form no part of the claimed invention.
